United States Patent Office

Des. 228,509
Patented Oct. 2, 1973

228,509

FOUR-CHANNEL, EIGHT-TRACK TAPE PLAYER

Richard H. Seager, Manlius, N.Y., assignor to
General Electric Company

Filed Nov. 29, 1971, Ser. No. 203,119

Term of patent 14 years

Int. Cl. D14—01

U.S. Cl. D26—14 B

FIG.1.

FIG.2.

FIG.3.

FIG.4.

FIG.5.

FIG. 1 is a front elevation view of a four-channel, eight-track tape player in accordance with my design; FIG. 2 is a top plan view;

FIG. 3 is a right side elevation view; FIG. 4 is a left side elevation view; and

FIG. 5 is a bottom plan view.

I claim:

The ornamental design for a four-channel, eight-track tape player, as shown.
